UNITED STATES PATENT OFFICE.

ALBERT BUCHHOLZ, OF MILWAUKEE, WISCONSIN.

GARBAGE-CAN COVER.

1,212,321.

Specification of Letters Patent. Patented Jan. 16, 1917.

Application filed April 5, 1915. Serial No. 19,395.

To all whom it may concern:

Be it known that I, ALBERT BUCHHOLZ, a citizen of the United States, residing at Milwaukee, in the county of Milwaukee and 5 State of Wisconsin, have invented a new and useful Improvement in Garbage-Can Covers, of which the following is a specification.

My invention relates to receptacles adapted to receive refuse, ashes or garbage 10 and its purpose is to provide a cover for said receptacle adapted to receive said refuse, ashes or garbage.

The object of my invention is to provide 15 a cover for a garbage can having a suitably formed compartment attached to same and providing means in said compartment to receive and admit garbage into a receptacle provided underneath said cover, and to prevent insects from entering into said receptacle. I attain these objects by the construction illustrated in the drawing in which—

Figure 1 shows a perspective view of a 20 garbage receptacle having a cover provided embodying my invention. Fig. 2 is a sectional elevation through said cover and showing the open and closed positions of the garbage receiving device. Fig. 3 shows a front elevation of the garbage receiving device.

Referring to Fig. 2, I secure to an ordinary cover 1 adapted to fit over a garbage receptacle 2 a suitably formed compartment 3 having formed thereon an extended horizontal flange 4 which is adapted to be attached to the cover 1 by means of rivets 5. 30 An opening 4^a is provided in the lower end of the compartment 3 and through the cover 1 through which the garbage is dumped into the receptacle 2 placed underneath said cover 1.

The vertical front wall 6 of the compartment 3 is formed at its upper end with an inclined front wall 7 having formed at the top edge thereof, at approximately right angles to said inclined front wall 7, a lip 8 extending into the interior of the compartment 3 at the top inclined opening 8^a thereof, the underside of said lip 8 providing a stop against which closes the projecting edge 9 of the garbage receiving plate 10, the other edge of which is attached to and forms a part of the pivoted cover 11 to which said garbage receiving plate 10 is secured on each side thereof, and closely fitting within the

side walls 12 of the compartment 3, by the 55 side plates 13 thus forming a receptacle adapted to receive garbage when said pivoted cover is lifted by the attached handle 14 and swung back until the edge 9 of the receiving plate 10 makes contact with 60 the lip 8 of the front wall 7.

A hinge rod 15 is suitably attached to the pivoted cover 11 where same is joined by the receiving plate 10 and extends beyond each side thereof and through the hinge plates 16 65 secured to the side walls 12 of the compartment 3 by the rivets 17.

A suitable edge 18 is formed on the pivoted cover 11 which fits over the inclined front wall 7 and the side walls 12 of the 70 compartment 3 thus providing a complete closure of the opening to said compartment 3. In use the pivoted cover 11 is lifted by means of the handle 14 and swung back, until the edge 9 of the receiving plate 10 75 meets the lip 8 of the front wall 7 at which point the material in said cover 11 will overbalance the material in the receiving plate 10 and hold the edge 9 of said receiving plate in contact against the underside of the 80 lip 8 thus keeping the compartment 3 closed to prevent flies and the like from entering within said compartment when said cover 11 is thus opened. Garbage may then be dumped on the receiving plate 10 which 85 will immediately descend by the added weight and close the cover 11 and dump the garbage through the opening 4^a in cover 1, into the receptacle 2. Cleanliness and convenience are thus secured by the device. 90

Having thus described my invention what I claim and desire to secure by Letters Patent, is—

In a device of the class described, the combination with a receptacle and a top therefor provided with an opening; of a housing permanently secured to said top and communicating with the opening in the latter, the rear wall of said housing being lower than the front wall thereof, whereby to provide rearwardly inclined upper edges on said housing, and the front wall of the housing having its upper portion thereof inclined rearwardly in a plane at substantially right angles to the plane of the upper edges 100 of the housing, a cover for the housing hinged to the upper edge of the rear wall of the latter, a receiving plate formed in

tegral with said cover at its hinged end and extending within the housing in a plane arranged at an obtuse angle to the plane of the cover proper, an inwardly projecting lip 5 provided on the upper edge of the front wall of said housing adapted to contact with the receiving plate to limit the outward swinging movement of said cover, side flanges connecting the cover with said receiving 10 plate, whereby to form substantially a re-

ceptacle therebetween and a handle on the outer face of said cover.

In testimony whereof I hereunto affix my hand in the presence of two subscribing witnesses.

ALBERT BUCHHOLZ.
